UNITED STATES PATENT OFFICE

GEORGE A. JEWELL, OF WILSON, NORTH CAROLINA, ASSIGNOR TO HACKNEY BROS.
BODY CO., A CORPORATION OF NORTH CAROLINA

REFRIGERATING APPARATUS

Application filed January 30, 1931. Serial No. 512,419.

This invention relates to refrigerating apparatus of the type employing solid carbon dioxide or the like as a refrigerant.

The apparatus herein shown and described is particularly adapted for use in connection with delivery trucks for ice cream and the like, although the apparatus may be employed in any other manner with the same advantages.

10 One of the objects of the invention is to provide, in a manner as hereinafter set forth, a refrigerating apparatus wherein gas emanating from a block of solid carbon dioxide is circulated around a container for articles 15 to be refrigerated and returned to the bunker containing the carbon dioxide.

A further object of the invention is to provide a refrigerating apparatus of the character aforesaid wherein the container for 20 the articles to be refrigerated is entirely enveloped by the gas during the circulation of the latter, and wherein the warmer portion of the circulating gas is directed back to the refrigerant bunker, thereby providing for 25 continuous circulation of the gas and completely eliminating dead spots around the container.

A further object of the invention is to provide a refrigerating apparatus of the character aforesaid wherein the water formed at the 30 top of the gas circulating space may be trapped at the top of the container and wiped off before the same collects at the bottom of the space, thereby preventing any 35 obstruction to the circulation of the gas by the freezing of water beneath the container.

With the foregoing and other objects in view, the invention consists of the novel construction, combination and arrangement of 40 parts as hereinafter more particularly described, and illustrated in the accompanying drawing, but it is to be understood that the description and drawing are to be taken as illustrative rather than limitative.

45 In the accompanying drawings in which like numerals are employed to designate like parts throughout the several views:

Figure 1 is a central vertical section through a refrigerating apparatus in accordance with this invention.

Figure 2 is a horizontal section taken at a point indicated by the line 2—2 of Figure 1.

Figure 3 is a horizontal section taken at a point indicated by the line 3—3 of Figure 1.

Figure 4 is a horizontal section taken at a point indicated by the line 4—4 of Figure 1.

Figure 5 is a horizontal section taken on the line 5—5 of Figure 2.

Referring to the drawings in detail, the numeral 1 indicates generally an insulating housing which may be of any well known construction, and which as shown consists of outer and inner walls 2 and 3 respectively having interposed therebetween a body of insulating material indicated at 4. The container 1 is provided with a suitable door 5.

Disposed within the housing 1 is a metal container 6 which is adapted to have stored therein articles to be refrigerated. The container 6 is provided with a door opening 7 in alignment with the door 5. Adjacent the door opening 7, the wall of the container 6 is flanged and secured in any suitable manner to an inwardly extending flange 7' formed on the housing 1 in encircling relation to the opening therein for the door 5. The container 6 is spaced from the side, end, and bottom walls of the housing 1 by means of suitable blocks 8, the container resting on such of the blocks as are disposed between the bottom thereof and the bottom wall of the housing. The side and end walls of the container 6 project upwardly beyond the top wall thereof to provide a continuous flange 9.

Extending through the top wall of the housing 1 and into the container 6 is a bunker 10 which is adapted to contain a block of solid carbon dioxide or the like. Preferably the bunker 10 will be formed with an open top and provided with a suitably insulated, removable closure member 11. In spaced relation to the bottom thereof, the bunker 10 is provided with a discharge port 12 which opens through an end wall of the container 6, and upon the opposite side thereof from the discharge port 12, the bunker 10 is provided with a return port 13 which is located between the top walls of the container 6 and housing 1. As clearly shown in Figure 2, the bunker 10 is disposed adjacent an end

wall of the container 6 and centrally with respect to the side walls thereof.

Seated on the top wall of the container 6 are a pair of deflectors 14 which extend in converging relation from upper corners of the container toward the bunker 10, terminating in spaced relation to the latter. In spaced relation to the bunker 10, and to the ends of the deflectors 14 adjacent thereto, are a pair of oppositely disposed deflectors 15 which extend in longitudinal alignment from the side edges of the container. Preferably the deflectors 14 and 15 are of channeled construction as will be observed from reference to Figure 4 wherein the deflectors 14 are shown in section. The deflectors 14 and 15 are substantially equal in height to the space between the container 6 and the top wall of the housing 1 and serve as spacers within such space. The spaced relation of the deflectors to each other and to the bunker 10 provide passages adjacent the port 13.

Centrally of the top wall of the housing 1 the insulating material thereof has embedded therein a receptacle 16 which is substantially in the shape of an inverted cup. Communication is established between the interior of the receptacle 16 and the space between the top walls of the container and housing by means of an opening 17 formed in the inner wall of the top of the housing. Opening through the receptacle 16 and through the outer face of the housing is a vent pipe 18.

In the operation of the apparatus, the carbon dioxide gas emanating from the solid block contained within the bunker 10 is discharged through the port 12 into the space between the container 6 and housing 1. The gas descends to the bottom of such space, thence along the bottom of the container and upwardly at the sides and one end of the latter to the top of the space. Owing to the disposition of the deflectors 14 and 15, the gas flowing to the top of the space will tend to converge toward the bunker 10, as indicated by arrows in Figure 2, and will be drawn through the return port 13 by the slight suction created therethrough by the escape of the newly emanating gas through the discharge port 12. Thus it will be seen that the gas emanating from the refrigerant block within the bunker will be continuously circulated around the container 6 and returned to the bunker. When the gas within the space surrounding the container has expanded sufficiently to creep along the upper wall of the space, the gas may escape through the opening 17 into the receptacle 16, thence through the vent pipe 18 to the outer air. The escape thus provided eliminates the possibility of the discharge of gas into the space in excess of the amount which can safely be confined within the housing.

It is to be noted that the construction of

the deflectors 14 and 15, and the positions thereof with respect to each other and to the bunker 10, entirely eliminates any dead spots above the container. The gas may freely pass through the deflectors and along opposite sides thereof to the return port 13. The flange 9 formed at the top of the container 6 is spaced from the top wall of the housing a sufficient distance to permit the rising gas to flow freely thereover, but is of sufficient height to prevent any water formed in the top of the space while defrosting from flowing down the sides and ends of the container.

In order that any water which collects on the top of the container may be readily removed, the top wall of the container slopes slightly from all directions toward the passages adjacent the port 13, thereby causing such water to travel in a direction parallel to the flow of the gas. In this manner the water will drain into the bunker 10 from where it may be readily mopped up. In the event that water is permitted to collect within the bunker 10 to such a depth that it will overflow through the port 12, the overflow may be drawn from the bottom of the gas space through a drain 19 provided for that purpose, thereby preventing any obstruction to the free passage of gas at the bottom of the space by the freezing of water therein.

It is thought that the many advantages of a refrigerating apparatus in accordance with this invention will be readily apparent, and although the preferred embodiment of the invention is as illustrated and described, it is to be understood that changes in the details of construction may be resorted to, so long as such changes fall within the scope of the invention as defined in the appended claims.

What I claim is:

1. In a refrigerating apparatus, a container for articles to be refrigerated and adapted to be contained within a housing in spaced relation to the walls of the latter, a bunker adapted to contain solid carbon dioxide extending into the container, said bunker having a gas discharge port and further having a gas return port in a higher plane than the discharge port, and a plurality of deflectors seated on the container and each having an end thereof terminating adjacent and in spaced relation to said return port.

2. In a refrigerating apparatus, a container for articles to be refrigerated and adapted to be contained within a housing in spaced relation to the walls of the latter, a bunker adapted to contain solid carbon dioxide extending into the container, said bunker having a gas discharge port and further having a gas return port in a higher plane than the discharge port, and a pair of deflectors extending in converging relation from upper corners of the container toward

- said bunker, said deflectors terminating in spaced relation to the bunker adjacent said return gas port.
3. In a refrigerating apparatus, a container for articles to be refrigerated and adapted to be contained within a housing in spaced relation to the walls of the latter, a bunker adapted to contain solid carbon dioxide extending into the container, said bunker having a gas discharge port and further having a gas return port in a higher plane than the discharge port, a pair of deflectors extending in converging relation from upper corners of the container toward said bunker, said deflectors terminating in spaced relation to the bunker adjacent said return gas port, and a pair of longitudinally aligned deflectors extending from side edges of the top of the container and terminating adjacent and in spaced relation to the converging pair of deflectors and said bunker.
4. In a refrigerating apparatus, a container for articles to be refrigerated and adapted to be contained within a housing in spaced relation to the walls of the latter, a bunker adapted to contain solid carbon dioxide extending into the container, said bunker having a gas discharge port and further having a gas return port in a higher plane than the discharge port, a pair of deflectors extending in converging relation from upper corners of the container toward said bunker, said deflectors terminating in spaced relation to the bunker adjacent said return gas port, and a pair of longitudinally aligned deflectors extending from side edges of the top of the container and terminating adjacent and in spaced relation to the converging pair of deflectors and said bunker, said deflectors being of channeled construction to permit the gas to flow therethrough and along opposite sides thereof.
5. In a refrigerating apparatus, a container for articles to be refrigerated and adapted to be contained within a housing in spaced relation to the walls of the latter, a bunker adapted to contain solid carbon dioxide extending into the container, said bunker having a gas discharge port and further having a gas return port in a higher plane than the discharge port, a pair of deflectors extending in converging relation from upper corners of the container toward said bunker, said deflectors terminating in spaced relation to the bunker adjacent said return gas port, and a pair of longitudinally aligned deflectors extending from side edges of the top of the container and terminating adjacent and in spaced relation to the converging pair of deflectors and said bunker, said return port being disposed at the opposite side of the bunker from the discharge port for creating a draft through the return port by the escape of the gas through the discharge port.
6. In a refrigerating apparatus, a container for articles to be refrigerated and adapted to be contained within a housing in spaced relation to the walls of the latter, a bunker adapted to contain solid carbon dioxide extending into the container, said bunker having a gas discharge port and further having a gas return port in a higher plane than the discharge port, and a plurality of deflectors seated on the container and each having an end thereof terminating adjacent and in spaced relation to said return port, said container having its top formed with a continuous flange to provide a water trap.
7. In a refrigerating apparatus, an insulating housing, a container therein in spaced relation to the walls thereof to provide a gas space enveloping the container, a solid carbon dioxide bunker extending through the housing and into the container, said bunker having a discharge port opening through the wall of the container, said bunker further having a gas return port located in a plane between the top walls of the container and housing, a plurality of deflectors seated on the container and providing passageways therebetween for the travel of gas along the top wall of the container to the return port, and means communicating with the top of the space between the container and housing for the escape of excess gas within such space.
8. In a refrigerating apparatus, a container for articles to be refrigerated and adapted to be contained within a housing in spaced relation to the walls of the latter, a bunker adapted to contain solid carbon dioxide extending into the container, said bunker having a gas discharge port and further having a gas return port in a higher plane than the discharge port, and a plurality of deflectors seated on the container and having their inner ends arranged in spaced relation to each other and to the bunker adjacent the return port to provide a plurality of passages adjacent the latter, said container having its upper face sloping from the edges thereof toward said passages.
- In testimony whereof, I affix my signature hereto.
- GEORGE A. JEWELL.
